RESPIRATOR

Nathan Schwartz, New York, N. Y.

Application November 16, 1935, Serial No. 50,116

3 Claims. (Cl. 128—146)

This invention relates to filter type respirators and comprehends an improved respirator which includes either an inexpensive, but effective, filter element which may be discarded when unfit for further use in lieu of a new element to replace the same, or a washable filter element which may be cleansed and reused.

More particularly the invention resides in an improved respirator of the indicated character which includes a substantially cup-shaped cover element of a size to enclose the nostrils and mouth of the wearer and means with which said element is detachably associated for holding the same in applied position and for exerting a pressure to impinge the marginal portion thereof against the face so as to prevent leakage and insure the passage therethrough of all of the air inhaled by the wearer.

With these and other objects in view, the invention is set forth in detail in the following specification and accompanying drawing wherein a preferred embodiment is disclosed, while the appended claims cover variations and modifications falling within the scope of the invention.

In the drawing:

Fig. 1 is a perspective view of the improved respirator in applied position.

Fig. 2 is a vertical sectional view therethrough on an enlarged scale.

Fig. 3 is a perspective view of the filter element removed from the holder.

Referring to the drawing by characters of reference, 10 designates a filter element preferably constructed of sheet material which is so fashioned as to present a cup-shaped structure of a size to enclose the nostrils and mouth of the wearer with the major portion thereof in spaced relation to the face except at the marginal portion thereof. The material may either be molded into this shape or, as illustrated, notched at 11 with the notched edges joined by a line of stitching 12 to impart the general cup-shape form thereto. If desired, the marginal portion may be covered with a strip of air impervious material 13, such as rubberized fabric which is attached thereto by stitching 14 to provide a nonirritating covering for contact with the face.

In order to provide means for holding the filter element in applied position and for exerting at the marginal portion thereof, a pressure to seal the same against the face, a member is utilized which may be of any desired type to perform the intended function. However, as illustrated, the member or holder consists of a face piece 15 conforming generally to that disclosed in my co-

pending application, Serial No. 44,694, filed October 12, 1935. The face piece or member 15 is constructed of molded rubber and conforms generally to the shape of the face in the region of the nose, mouth and chin, and includes a nose covering portion 16 having a lower horizontal wall 17 provided with a depending tubular boss 18, and further includes a mouth covering portion 19. The rear margin of the face piece is provided in the region of the nose and chin with inwardly directed angularly disposed flanges 20 and 21, the free edges of which flanges are respectively contoured to fit over the bridge of the nose and the lower portion of the lower lip, while the rear face of the lower flange 21 is adapted to contact with the chin immediately below the lower lip. The face piece is also formed with cheek flaps 22 adapted for flat contact with the cheeks of the wearer throughout a substantial area thereof. The cheek flaps have attached thereto the ends of a supporting band 23 for holding the face piece in applied position. The face piece in this instance is preferably provided with any number of air passages 24 in addition to the air passage defined by the tubular boss 18.

The filter element 10 is applied to the inner or hollow side of the face piece 15 and suitable means is provided for detachably associating the filter element with the face piece, which means in the present instance is disclosed as strips of adhesive tape 25 which are adhesively attached to tabs 26 formed at the upper portion of the filter element 10 the protruding ends of the tape strips 25 being adhesively connected with the exterior of the face piece 15. When the filter element is thus associated with the face piece or hollow member 15, the respirator is donned and the supporting band 23 causes the marginal portion of the face piece to exert a pressure against the marginal portion of the filter element 10 to impinge the same against the face of the wearer so as to seal said filter element at its marginal portion against leakage of air therearound.

In some instances, the filter element 10 may be made of an inexpensive material which may be discarded when unfit for further use in lieu of a new element to replace the same, while in other instances the filter element may be made of a material which may be cleansed and reused.

Obviously, when the respirator is in applied position, all of the air breathed by the wearer must pass through the filter element so as to separate therefrom any injurious foreign matter such as dust, dirt or the like. It will also be apparent that the filter element may be readily

changed or renewed by simply detaching the adhesive strips or other equivalent fastening means from the face piece. It will also be observed that due to the cup-shaped configuration of the filter element 10, the major portion of the same will be disposed out of contact with the face of the wearer except at the marginal portion and where said marginal portion is provided with a covering strip 13, the wearer is relieved of the irritating nature of certain types of filter elements which are of felt, wool or equivalent materials.

What is claimed is:

1. A filter type respirator including a filter element adapted to enclose the nostrils and mouth of the wearer and fashioned so as to be disposed in spaced relation to the face except at the marginal portion thereof, a member having air passages therethrough, said member overlying and detachably associated with the central portion of the filter element with the marginal portion of the filter element extending therebeyond, and means connected to said member for holding the same in applied position and for exerting pressure to impinge the filter element against the face of the wearer adjacent the marginal portion of said filter element.

2. A filter type respirator including a filter element adapted to enclose the nostrils and mouth of the wearer and fashioned so as to be disposed in spaced relation to the face except at the marginal portion thereof, a strip of air impervious material secured to and extending around the marginal portion thereof and a member having air passages therethrough and with which said element is detachably associated to constitute means for holding the same in applied position and for exerting a pressure to impinge the covered marginal portion against the face of the wearer.

3. A filter type respirator including a substantially cup-shaped filter element adapted to enclose the nostrils and mouth of the wearer, a member for holding the filter element in applied position and for exerting at the marginal portion of said element a pressure to seal the same against the face of the wearer, means for detachably associating the filter element with the member, said means comprising adhesive strips on the filter element having extending portions adhesively attached to the member.
